UNITED STATES PATENT OFFICE.

JOSEPH FLEISCHMAN, OF KEW GARDENS, NEW YORK.

LEGGING.

Application filed November 16, 1927. Serial No. 233,569.

My present invention is concerned more especially with leggings intended to be discarded after a single use in a shower or storm.

5 It is an object of the invention to provide a legging of extremely simple and inexpensive construction, which can be readily made of paper or other inexpensive fabrics, which may be applied to the person with facility, 10 and which will not only fit snugly and afford adequate protection, but will be attractive in appearance.

Another object is to provide a legging of the above type, one size of which will fit 15 persons of a considerable range of girth.

In the accompanying drawings, in which are shown one or more of various possible embodiments of the several features of this invention,

20 Fig. 1 is a perspective view illustrating the legging as applied,

Fig. 2 is a plan view illustrating the completed legging in open position,

Fig. 3 is a view in transverse cross-section 25 of the closed legging and

Fig. 4 is a plan view illustrating the constituent blanks making up the legging, and the relative positions thereof prior to assembly.

30 Referring now to the drawings, the legging is preferably made of blanks of limber, waterproof or water shedding material, such as paraffin or oil paper on which may be imprinted designs or patterns simulating the 35 appearance of the goods of which ordinary leggings are made.

Preferably the legging is composed of three blanks, a main or central blank 10 and two lateral or side blanks 11 and 12.

40 The main blank has curvature along its sides approximating that of the human calf, and is widened near the bottom to form a toe or instep portion 13 and a heel or ankle portion 14. The lateral blanks 11 and 12

45 have respectively approximately straight outer edges 15 and 16 but at their inner edges have respectively curvatures 18 and 19 substantially precisely the same as those of the main blank 10. The respective blanks

50 are attached together with the concavities of their curvatures facing each other, as suggested in Fig. 4. While any of a variety of modes of attachment may be employed within the scope of my invention, I prefer 55 to stitch these blanks together as at 20 Fig. 3. The resultant legging will thus be

shaped to provide extra material at the foot for snugly engaging the instep and the heel, as is apparent from the drawings.

A lace or tape 21 is attached near the lower edge of the main blank 10 preferably substantially at the middle thereof. For attachment I may use the usual rivet and wafer 22 known as a "Taylor" fastener, and commonly employed for stationery. Near 65 the lateral edge 15 I provide additional fasteners preferably equidistant wafer or "Taylor" fasteners 23. These fasteners include a wafer 23' near the lower edge of the lateral panel 11 and a succession of wafers 23 preferably at equal intervals along said edge including a wafer 23² near the upper edge of the legging. The opposite lateral panel 12 is provided with similar wafers 24 which are at levels intermediate those of the wafers 75 23.

The legging is applied to the person by passing the forward shaped portion 13 of the toe over the instep of the foot, then folding the lateral panels 11 and 12 about the calf 80 to completely encircle the same, with the panel 11 overlapping the edge of the panel 12. The lace 21 is then simply drawn from the inner side of the shoe under the arch of the foot, anchored about wafer 23' and 85 then laced back and forth in a zig zag path as shown in Fig. 1 alternately about a wafer 24 of blank 12 and a wafer 23 of blank 11, and finally lapped once or twice around the extreme or uppermost fastener 23². 90

Preferably the line of fasteners 24 are not as near edge 16 as are wafers 23 to edge 15. Accordingly edge 15 will come close to the line of fasteners 24 without covering them, when the legging is applied to a small 95 calf as shown in Fig. 1, while, when the protector is applied to a large calf, a wider area of panel 12 will be exposed beyond the edge of panel 11.

When the legging is thus applied to the 100 foot, the single lace performs the double function of anchoring the legging in its entirety under the arch of the foot, so that it cannot slip or creep upward, and snugly clasping the legging about the calf. The 105 seams 20 extend substantially along the median plane of the foot and leg and constitute a brace or stiffener maintaining the form of the legging.

The inner part of the lace adjacent the 110 wafer 22 serves as an effective arch strap since by its attachment at wafer 23', it is

- drawn taut substantially into engagement with the sole of the foot of the shoe and the opposite lower edges of the legging into snug engagement with the shoe. The slack or slippage is thereby avoided which would be incurred where the ends of the arch strap attached at substantially higher level. Moreover, the continuation of the arch strap as a lace for holding the legging about the calf aids in distributing the strains exerted by the arch strap over various parts of the fabric, and the fabric will, therefore, endure the strain without the need for local reinforcement.
- 15 While the legging is primarily intended for but a single use, it will be understood that it can be readily removed from the foot without destroying any part thereof, and is thus capable of re-use.
- 20 It will thus be seen that there is herein described an article in which the several features of this invention are embodied, and which attains the various objects of the invention and is well suited to meet the requirements of practical use.
- 25 As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.
- 30 Having thus described my invention, what I claim as new and desire to secure by Letters Patent is:—
1. A legging comprising a blank having fastener elements near the lateral edges thereof and a flexible binder anchored near

the lower end of said blank, substantially midway between the lateral edges, whereby the legging encircled about the calf may be secured in position by passing the flexible binder under the arch of the shoe and lacing it with respect to the fasteners. 45

2. A calf protector comprising a composite blank of paper having substantially straight lateral edges and including extra material near the bottom thereof to accommodate the curvature of the instep and heel of the foot, wafer fasteners near opposite lateral edges of the blank in a zig zag arrangement, and a lace attached near the lower end of the blank substantially midway 50 between the fasteners, whereby in application, the lace may be extended under the arch of the shoe and strung about the successive wafers. 55

3. A legging comprising a blank having a fastener element near one of the lateral edges of said blank and substantially at the lower end thereof, a second fastener element near the lower end of said blank substantially midway between the lateral edges thereof, 60 flexible binder means including a portion that may be extended under the arch of the foot and secured to said fastener elements near the lower edge of the blank, and fastener elements near the lateral edges of the blank and distributed substantially along the length thereof, said flexible binder means including a portion that may be laced with respect to said fasteners to maintain the legging in position about the calf. 70 75

Signed at New York, in the county of New York and State of New York this 15th day of November, A. D. 1927.

JOSEPH FLEISCHMAN.
